UNITED STATES PATENT OFFICE

ELDRID L. BOUTON, OF PHILADELPHIA, PENNSYLVANIA

ENVELOPE-FILLING MACHINE

Application filed January 16, 1929. Serial No. 332,943.

This invention relates to an envelope filling machine and more particularly it is adapted to receive envelopes in a magazine with the envelope flaps in open condition, feed them through the machine and position them so as to receive enclosures and at the same time feed the enclosures, either one or more from their magazines in timed relation, insert the same in the envelopes which have the side walls thereof distended to receive the enclosures, and after receiving the enclosures the filled envelope is discharged from the machine to a stacker by means of which the envelopes are arranged in orderly fashion and can be removed from the machine in stacked formation.

This machine is adapted to fill envelopes that have already had the flaps thereof opened by treatment in a machine such as illustrated in my copending application Serial No. 319,986, filed November 16, 1928, and is not to be confused with a machine in which the envelope flap is opened and the filling operation subsequently performed all in the single machine.

An object of the present invention is to provide a machine in which the proper positioning of the envelope to receive its enclosure is insured by providing means which automatically register the envelope so that it will properly receive its enclosure, this registration being both with reference to the vertical and the horizontal.

Another object of the present invention is to provide adjustable parts throughout the machine by means of which a machine can accommodate itself to envelopes of various sizes and shapes as well as various gauge stocks thereby rendering the same practically universal in operation.

An additional object is to automatically stop the machine in the event that the stacker mechanism is completely filled or in the event of the failure of an envelope to be fed through the machine and in addition to provide means for manually stopping the machine from either end thereof.

An additional object is to provide positive means for engaging the envelope and distending the mouth thereof so as to insure its

proper positioning to receive its enclosure and in the means for adjusting said mechanism to accommodate envelopes of various size and shape together with means for quickly disassembling said mechanism when it is desired to gain access to parts of the machine for purposes of cleaning or repairing.

Other objects and advantages will be evident as the description proceeds, it being understood, however, that changes in the proportion, minor details of construction or finish of the various parts may be resorted to without departing from the spirit of the invention as defined in the claims hereunto appended.

In describing the invention reference will be had to the accompanying drawings forming part hereof and in which corresponding parts are similarly numbered throughout the various views.

Figures 1 to 5 are diagrammatic illustrations of the sequence of operation.

Figs. 33 and 34 are details of the same mechanism.

Fig. 35 is a detail perspective view of means 70 for adjusting the feed of the main feed roller.

Fig. 36 is a side view of the pawl plate used in driving the feed roller.

Fig. 37 is an end view partially in section 75 of the same plate.

Referring more particularly to the drawings and especially to Figs. 1 to 5, the general operation of the machine will first be described.

The machine comprises an envelope magazine indicated at 1 which is adapted to contain stacked envelopes with the flaps thereof in open condition and enclosure magazines 2 and 3 which are adapted to receive enclosures in stacked relation it being understood, of course, that any manner of magazines may be employed depending upon the character of the work to be done.

Immediately below each of the magazines 90 I provide a feed roll which is adapted to support the lower edge of the lowermost envelope or enclosure and upon rotation of these feed rolls the envelopes and enclosures respectively are intermittently fed from the magazines in timed relation so that upon reaching 95 a predetermined location the envelope mouth will be distended and the enclosures inserted therein.

The feed roll 4 beneath the envelope magazine 1 feeds the envelope between the rollers 100 5 which in turn pass the envelope downwardly between the rollers 6 and the adjustable deflecting plate 7.

Further movement of the envelope causes the same to be fed between the oscillating plate 8 and the stationary plate 9 as clearly indicated in Fig. 2 and the envelope continues its movement between the plates 8 and 9 until the lower edge of the envelope engages the register bars 18.

At this time the plate 8 is oscillated by mechanism which will be described herein-after so as to clamp the flap of the envelope between the upper edge of plate 8 and the lower edge of deflector plate 7.

It will thus be seen that the envelope is now held in a stationary position with the flap thereof securely gripped between the oscillating plate 8 and the adjustable deflecting plate 7.

When the envelope is in this condition the distending fingers 19 move into position to grip the upper edge of the back of the envelope and is thereupon retracted so as to pull the back of the envelope away from the face thereof and maintain the envelope mouth in distended condition as clearly illustrated in Fig. 3.

At this time the enclosures from the magazines 2 and 3 have been fed through the ma- 100

chine in timed relation so that they meet each other and pass between the rollers 11 and 12 in superposed condition and are directed against the curved rear face of the adjustable deflecting plate 7 by means of which they are fed downwardly into the distended mouth of the envelope.

Immediately before the envelope receives its enclosure the register bar 18 is withdrawn, 10 at which time the envelope flap is clamped by the plate 8 so that the sole supporting means for the envelope is the clamping action on the flap. The envelope is, therefore, suspended by means of its flap and upon insertion of the enclosure in the envelope while in this suspended condition a downward tension is exerted on the envelope so as to insure the enclosure properly passing into the envelope. After the enclosure has been inserted in the envelope the plate 8 oscillates to its released position where it is in position to receive the next succeeding envelope and the envelope which has been filled is accordingly freed from clamping between the deflecting plate and the oscillating plate and falls between the endless belts 20 and 21 where it is fed downwardly to the stacker mechanism.

By referring to Fig. 5, it is believed that this operation can be clearly understood and in this figure the stacker mechanism is illustrated diagrammatically as comprising slide rods 28 carrying thereon guide rods 25, the vertical face of which is in alignment with the pass between the endless belts 20 and 21 so that a filled envelope coming from the endless conveyors slides downwardly along the vertical face of the guide rods 25 and into contact with the stacking roller 26 contacting therewith at approximately the point 27. 30 The stacking roller 26 is provided with a series of enlargements 29 and has the face thereof composed of friction material so that as the roller 26 is rotated it forces the filled envelope downwardly against the rods 28 and against the back plate 31 which is carried by the slide 32 and which slides upon the rods 28.

It is believed to be obvious that at the start of operation the back plate 31 is placed 50 close to the guide rods 25 and that as the envelopes are successively fed from the endless belts 20 and 21 the roller 27 holds the lower edge of the envelope into engagement with the rods 28 and against the back plate 31 which is adapted to slide rearwardly to accommodate each succeeding envelope until the magazine is completely filled, at which time means are provided for automatically stopping the operating parts while still permitting the power mechanism to continue its motion.

From an examination of Figs. 1 to 5 of the drawing it is believed to be evident that the enclosures are fed from the magazines 60 2 and 3 respectively by a series of feed rolls,

those cooperating with magazine 2 being indicated at 10 and those cooperating with magazine 3 being indicated at 13 and 14.

From the magazine 2 the enclosure is fed by means of the roller 4 between the feed rollers 10 and the feed rollers 11 and 12 into engagement with the curved rear face of the adjustable deflecting plate 7 by means of which they are given a vertical position and inserted into the mouth of the open envelope.

Enclosures from the magazine 3 are fed by means of the roller 4 between the rollers 13 and 14, 15—16, where they assume a horizontal position as indicated at 17 and pass forwardly to meet the enclosure from the magazine 2 as clearly illustrated in Fig. 3 where it likewise is curved to a vertical position by means of the deflector plate 7 and inserted in the envelope.

From the foregoing it is believed that the general operation of the machine can be clearly understood and the construction of the various parts and the mechanisms for accomplishing these results will now be described.

Referring now to Figs. 6 and 7 it will be seen that the machine comprises the side frames X and Y which are spaced apart by means of suitable tie rods 32' and between which the rotating feed rollers are mounted.

On the upper edge of the frames X and Y are provided the magazines for the envelopes and the enclosures, the envelope magazine being illustrated at 1 and the enclosure magazine being illustrated at 2 and 3.

Immediately below and adjacent the front end of each magazine I provide the intermittently operating feed rolls 4 which are adapted to receive and support the lower edge of the lowermost envelope or enclosure of each stack and as heretofore described the envelopes are fed by means of this roller 4 to a vertical position for the reception of the enclosures. Likewise the enclosures are fed into said envelope and the feed for the enclosure from the magazine 3 has already been described as passing between the rolls 13 and 14, 15, 16, 16', 17', 16'', 17'' to the rolls 11 and 12. It is to be noted that although the rolls 4 are given an intermittent motion for feeding envelopes and enclosures from the magazines in an intermittent manner, the other feed rolls in the train are driven continuously in view of the fact that these rolls are all suitably geared together as clearly illustrated in Fig. 8 where the gear train is generally indicated at D on one side of the machine, and in Fig. 9, the gear train is indicated at C on the other side of the machine.

Any suitable gearing may be resorted to but it is believed to be solely a question of mechanical skill, and, therefore, it is not believed necessary to describe in detail the specific type or manner of gearing.

As heretofore described the envelope pass-

ing from the magazine 1 finally enters between the oscillating plate 8 and the stationary plate 9. At the proper moment the horizontal register bars 18 are fed forward by 5 means of a bell crank 34 and cam lever 35 which is pivoted to the bell crank 34 at point 36, the position of the horizontal register 18 at that time being clearly illustrated in Figs. 1 to 3 and it arrests and registers the envelope between plates 8 and 9. By projecting 10 the register bar 18 into the path of travel of the envelope the envelope is caused to assume its proper vertical position and I provide a pin 57 mounted in the block 58 which 15 is slidable with the shaft 59 and operated by the cam lever 60, as will be described hereinafter which causes the envelope to be registered horizontally so that it will be in position to receive the enclosures from the magazines 2 and 3.

After the envelope has been filled and released from engagement with the plates 8 and 9 it drops between the endless belts 20 and 21 which move the same downwardly. However, 25 in this downward movement the filled envelope is checked by means of a secondary stop 37 and a detector pin 38 is permitted to be snapped forward by means of the spring 39 into engagement with the envelope, the pin 30 38 and stop 37 being adapted to pass between the endless belts 20 and 21.

If the envelope is in proper position between the belts 20 and 21 forward movement of the detector pin 38 will be arrested by the 35 envelope and the automatic stop mechanism will, therefore, not be operated, but if no envelope has passed between the belts 20 and 21 to the stop 37 the detector pin 38 will continue its forward movement until it engages 40 with the plate 46, which is adapted to prevent buckling of the envelope or injury thereto by the detector pin 38.

In this continued movement of the detector pin 38 which is carried by the oscillating 45 lever 40 the lower end of the lever 40 which is provided with a cam face 41 will engage with a pin 42 which is integral with the shaft 43 as will be illustrated later and will cause the shaft 43 to trip a latch mechanism, thereby 50 causing the clutch carried by the shaft 44 to become disengaged and stop the machine, that is to say, the clutch will be disengaged so that the operating parts of the machine will cease functioning, although the motor driven 55 pulley 45 continues its rotation so that upon re-engagement of the clutch faces the machine will again be put into operation.

It is evident, therefore, that envelopes not feeding through the belts indicates either that 59 no envelopes are being fed from the magazine 1 or that the envelopes have become clogged somewhere in the machine above the stop. In either case it is essential that the machine be stopped to avoid injury both to the material being operated upon and to the various

parts of the machine and it is for this reason that I provide the automatic stop mechanism. It is believed to be clear that if an envelope is passing in proper position between the belts 20 and 21 the stop 37 and detector pin 38 will 70 not operate to automatically stop the machine, but the envelope will continue its movement between the belts and finally assume the position as indicated at 47 in the stacking mechanism.

In addition to the mechanism for stopping the machine in the event of jamming or failure of envelopes in the magazine 1, I provide additional means for automatically stopping the machines when the stacking mechanism has become filled. This is important as otherwise constant attention would be needed by the operator and if the operator neglected to remove the filled envelopes when the stacker was filled they would pile up upon 80 each other, thereby injuring the machine and completely ruining the article being treated.

The mechanism for automatically stopping the machine upon the filling of the stacking mechanism is illustrated in Fig. 6, where it will be seen that as the stacker is successively filled the back plate 31 is gradually pushed rearwardly until it reaches the end of its movement at which time the downwardly extending lug 50 integral with the plate 31 engages the stud 51 on the rocking lever 52 which is pivoted to the side frame at the point 53 where upon the end of the lever 52 carrying the stud 51 is depressed. The other end of the rocking lever 52 is, accordingly, moved in an upward direction and engages with the end of the sliding bar 54 which is likewise secured to the side frame by means of bolts 55 passing through elongated slots 56 in the bar 54 so that upon upward movement of the end 100 of the lever 52 the bar 54 is given a vertical movement and engages with the pin 42 carried on the shaft 43 to rotate the same, it being noted, however, that the bar 54 engages the pin 42 on an end opposite to the end 105 which is engaged by the cam face 41 of the lever 40.

The function, however, is the same, that is, by rotation of the shaft 43 either by the angular face 41 or by the rod 54, the clutch on the shaft 44 is disengaged, thereby stopping movement of the operating parts.

The specific construction and operation of the clutch mechanism will be described hereinafter more specifically.

Mouth distending mechanism

It has been stated hereinbefore that when the envelope is clamped between the oscillating plate 8 and the deflector plate 7, the fingers 19 come into position to grip the upper edge of the back of the envelope and distends the mouth thereof to receive its enclosure. This mechanism will now be described.

By referring to Fig. 12 it will be seen that the fingers 19 are pivoted on the shaft 66 which extends between the side frames X and Y of the machine and the nose 67 thereof is caused to move in a vertical plane by means of the cam 68 rotating with the cam shaft 62, the motion being transmitted from the cam 68 through the levers 69, 70, 71, the lever 69 being fastened to and oscillating with the shaft 72 and the levers 70 are likewise fastened to each end of the shaft 72.

By referring to Figs. 14 and 15, it will be seen that the end of each lever 70 is provided with a recess 73 communicating with an entering slot and that this recess is adapted to receive the reduced portion 74 of a stud 75 (Fig. 16) which is threaded into the end of the shaft 76.

The lever 71 is bolted by means of the stud 75 against the face 77 of the shaft 76, the reduced portion 74 resting in the seat 73, but in order to prevent accidental displacement of the shaft 76 from the seat 73, I provide a spring retaining arm 78. This spring arm 78 is secured to a stud 78^a on the lever 70 and passes between supporting studs 78^b integral with the lever 70 and disposed on opposite sides of the flat portion of the spring and has at its end a depressed portion 78^c which is adapted to encircle the reduced portion 74 of the stud 75, thereby maintaining the shaft 76 in the seat 73. The spring 78 is in addition provided with an extending lip 78^d which provides a finger lever by means of which the spring can be raised so as to release the shaft 76 and permit its removal from the seat 73 of the lever 70.

It will be seen, therefore, that under ordinary conditions of vibration due to operation of the machine, the shaft 76 will be maintained in position and that a pull sufficient to overcome the tension of the spring 78 is necessary to release the shaft.

The purpose of removably mounting the shaft 76 in the lever 70 is to permit the envelope distending mechanism to be temporarily withdrawn from place for purposes of adjusting or repair and quickly snapped again into proper position.

In order to accomplish this removal I also mount the fingers 19 removably and by again referring to Figs. 12 and 17, it can be seen that the lever 80 is provided with a bayonet slot 80^a passing through the side edge of the lever 80 and into which the pivot shaft 66 for the lever 19 is passed. In order to maintain the shaft 66 in the bayonet slot I provide the spring 80^b attached to the arm 80 by means of the stud 80^c and passing between the studs 80^d located on opposite sides of the spring and provided at the upper end of the spring 80^b is a trough 80^e which is adapted to receive the shaft 66, thereby supporting the same in position. The spring 80^b is also provided with a finger piece 80^f by means of

which the shaft may be removed from its bearing. It can be seen by referring to Fig. 17 that the fingers 19 are rigidly secured to the shaft 66 by means of the screw 81 passing through the collar integral with the fingers 19 and it will be seen, therefore, that upon release of the shaft 66 from the slot 80^a and the release of the shaft 76 from the seat 73 the fingers may be completely swung out of position so as to permit access to parts of the machine that are normally inaccessible because of the envelope mouth distending mechanism.

An additional reason for removably mounting the shafts 66 and 76 is to permit of the adjustment of fingers 19 on the shaft 66 to accommodate the machine to the particular envelope that is being filled, the machine being adapted to operate on various sizes of stock as has been stated heretofore.

In Fig. 12 the finger 19 is shown in a low position and clearing the circumference of the feed rollers 12. Nevertheless, it takes a higher position at times that causes it to move upward between the rollers 12. To adjust the fingers 19, therefore, on shaft 66 would be extremely difficult unless it were possible to move the fingers 19 clear of the rollers 12 and make such adjustment as would be necessary and then place the fingers 19 back into position and the shaft 66 in its bearing.

Furthermore, most of the jamming of the machine, if an envelope should tear or an enclosure become creased, is likely to happen between the plates 8 and 9. To facilitate the removal of the crumpled envelope or enclosure, the mechanism comprising the fingers 19, levers 71, shafts 66 and 82 can be quickly swung out of position by pulling the shafts 66 and 76 out of their sockets as before described to permit access to the plates 8 and 9.

The distending fingers 19 are given a substantially rectangular movement, that is to say, it moves in a horizontal path inwardly above the upper edge of the back of the envelope, then vertically downwardly into engagement with the top edge of the back of the envelope, then rearwardly to pull the rear of the envelope away from the face thereof and again vertically to the starting position. As has already been described the vertical movement of the fingers 19 is imparted by the cam 68. The horizontal movement is accomplished by means of the cam 83, likewise carried by the shaft 62, lever 84 and double levers 80 and 80'.

On the lever 80' I provide an angular extension 80² and on the lever 80 a similar angular extension 80³ through which is passed a bolt 80⁴ encircled by the spring 87 which bears at opposite ends against the angular extensions 80² and 80³ for normally holding the extensions in separated condition. On the end of the bolt 80⁴ I provide a knurled knob 89 screw threadedly engaging the bolt 130

80⁴ so that by adjusting the knurled knob, the movement between the levers 80 and 80' can be varied.

The purpose of this spring connection between the levers 80 and 80' is to provide a yielding contact of the fingers 19 with the plate 8 during its horizontal movement to engage the envelope. This yielding movement also permits the fingers 19 to accommodate themselves to envelopes of various stock.

In addition to the yielding movement of the fingers 19 during their horizontal movement I also provide means for producing a yielding movement of the fingers 19 during their vertical movement. This is accomplished by means of the structure shown in Fig. 14 in which the link 71 is provided with an elongated slot 71' encircling the shaft 82 and has at its upper end an angular extension 70² carrying the bolt 70³ encircled by the spring 70⁴ bearing against the angular extension 70² at one end and against the shaft 82 at the other end and the bolt 70³ is screw threaded to be engaged by the knurled knob 88 so that by adjustment thereof the distance between the shaft 82 and the extension 70² can be varied and at the same time provide for a yielding and adjustable support of the fingers 19 in their vertical movement.

From the foregoing, therefore, it is to be seen that the noses 67 of the envelope opening fingers 19 can be caused to move in one direction by a cam and in another direction by spring pressure and to be moved vertically by cam action in one direction, and a spring counter action. It will also be seen that by adjustment of the knobs 88 the relative vertical position of the noses 67 can be altered independent of the various lever links and by adjustment of the knob 89 the horizontal position of the nose 67 can be altered irrespective of the lever or pivot positions.

Envelope positioning and clamping mechanism

It has heretofore been stated that the envelope is received between the oscillating plate 8 and the stationary plate 9 and has the flap thereof clamped between the upper end 50 of the plate 8 and the adjustable deflector plate 7. The mechanism for oscillating the plate and for projecting the register bars 18 into the path of travel of the envelope as well as the horizontal registering mechanism, will now be described.

Referring now to Figures 18 to 20 inclusive it will be seen that the oscillating plate 8 is provided with an ear 8^a projecting from the rear face thereof and is provided with an aperture and that secured to the plate 8 is a lever 89' pivoted to the ear 8^a by means of the pivot 90.

Riveted in the plate 8 and extending from the rear face thereof is a screw threaded stud 91 which passes through an angular lug 92

on the lever 89' and between the plate 8 and the bent lug and surrounding the screw threaded stud 91 is a spring 93 which normally tends to swing the lug 92 away from the plate 8. In order to limit swinging of this lever 89' I provide a second angular extension 94 on the lever 89' and pass therethrough a screw 94' which is adapted to engage the plate 8 so that by adjusting of the screw 94' the pivotal movement of the lever 89' is limited. On the stud 91 is a nut 91' by means of which tension on the spring 93 may be varied. It is to be noted that the lever 89' is substantially triangular in shape and at the apex of the triangle is a roller 97 which contacts with the cam 96 and is, therefore, periodically swings into clamping position the plate 8. It is to be noted that the plate 8 is pivoted to the shaft 95 at its lower end and at its upper end the plate is offset as at 97' so as to provide a ledge which coincides with the lower portion of the deflector plate 7 when the oscillating plate 8 is in its clamping position.

Fig. 20^a illustrates how the plate 8 when clamped against the lower portion of the deflector plate 7 will grip the flap end of the envelope 98 at the right angle turn 99.

Counteracting against the spring 93 is the spring 100 secured at one end to the plate 8 and at the other end to the shaft 59 which tends to retain the plate 8 also in open position and the roller 97 against the cam 96.

From the foregoing it will be seen that the plate 8 has a yielding clamping action due to the spring 93 cooperating with the angular lug 92 so that regardless of the thickness of the paper which constitutes the envelope it will clamped between the plate 8 and the deflector plate 7 and no adjustment of this plate will be necessary since the yielding contact permits this plate to automatically take care of variations in thickness of stock being operated upon.

In addition to the vertical adjustment of the fingers 19 by means of the knob 88 I further provide for the adjustment of the register bars 18 to accommodate envelopes of various shapes and sizes and in Figs. 18 and 19 it will be seen that the register bar 18 is supported adjacent its forward end on the bar 102 which is suspended at each end by means of links 103 rotatable with the shaft 95. Integrally fastened to the shaft 95 and on the outside of the frame X is a slotted link 104 (Figure 20) provided at its upper end with a handle 104' and fixed at its lower end on the shaft 95. Rigidly secured to the frame X is a screw threaded stud 105 which projects through the slot 105' in the slotted plate 104 and has threadedly engaging therewith the knurled knob 105².

It will thus be seen that by loosening the knob 105² and swinging the slotted plate about its pivotal point by means of the handle 104

104' the shaft 95 will be rotated and consequently the bar 102 which, bearing upon the register bar 18, raises or lowers the stop to the desired position.

5 In Figure 19 I have also illustrated the manner of adjusting the roller 12. In Fig. 19 the roller 12 is shown in section as well as a portion of the shaft 12' on which the roller 12 is supported. In one side of the shaft 12' 10 I provide a keyway which is adapted to receive a crimped spring 106 having upturned ends 106' adapted to engage on opposite sides of the roller and this manner of mounting serves the double function of acting as a 15 means for keying the roller 12 to its shaft 12' and due to the crimped construction of the spring 106 acts as a friction member for retaining the roller 12 in any position along the shaft 12', it being found necessary to adjust the roller 12 of the shaft 12' to accommodate the same to various size envelopes.

In Figs. 18 to 20 inclusive, I have also illustrated the manner of adjusting the deflector plate 7 in order to vary the gap at the point 107 to accommodate material of 25 various thicknesses. This adjustment of the deflector plate 7 is accomplished by providing at opposite ends of the deflector plate 7 the reduced hubs 108 provided with sockets 30 108' into which is screwed the bolt 109 having a reduced portion 109' fitting the socket 108' in the hub 108. Fastened integral with the hub 108 is a gear segment 110 which meshes with the pinion 111 carried on the inner end of the shaft 111' so that by turning the shaft 111' the gear segment is rotated and consequently the deflector plate 7.

In order to provide means for rotating the shaft 111', I provide an elongated slot 113 in 40 the knob 114 which is adapted to receive the pin 114' projecting from the shaft 111'. The end of the shaft 111' is threaded to receive the lock nut 115 which screws on to the threaded shank 112 and by continued rotation jams the 45 knob 114 against the side frame X, thereby locking the pinion 111, gear segment 110 and deflector plate 7 in the desired position.

The mechanism constituting the side register motion by means of which the envelope 50 is shifted longitudinally into proper position to receive its enclosure consists of a shaft 59 slidably carried in the side frames X and Y and retained therein by means of a pin 117 projecting from the shaft 59 and operating in 55 the slot 117' in the side frame. Mounted on the shaft 59 is the block 58 in which the register pin 57 is adjustably secured by means of the thumb screw 116. Integral with the shaft 59 and extending downwardly there- 60 from is the lug 119 and this lug is held in engagement with the edge of the horizontally bent lug 120 on the cam lever 60 by means of the spring 121 which encircles the shaft 59 and has one end thereof bearing against the 65 side frame Y and the other end against the

stud 119. The horizontally bent lug 120 is provided with a cam surface 122 (Fig. 20c) so that upon operation of the cam lever 60 it will be seen that the cam surface engaging the lug 119 will reciprocate the shaft 59 in its 70 bearings and accordingly, the pin 57 will act against the side edges of the envelope to register the same horizontally, it being noted that the pin 57 operates through the slots 123 in the plate 8 as clearly indicated in Fig. 19. 75 The lug 120 extends laterally from the upper end of the cam lever 60 and the end edge of the lug 120 is cut at an angle to form the cam surface 122. This end edge which forms the cam surface 122 wipes against the depending lug 19 of the shaft 59 and positively moves the same in one direction against the action of the spring 121.

The means for operating the cam lever 60 is clearly shown in Fig. 18 where it will be 80 seen that the cam lever 60 carries the roller 61' contacting with the cam 96 to automatically oscillate the cam lever 60 and thus produce the lateral movement of the register pin 57.

The foregoing description with reference to Figs. 18, 19, 20, 20a, 20b and 20c show that I have provided means for adjusting the deflector plate 7 from the outside of the machine to obtain a varying gap between the deflector plate 7 and the feed roller 12, thereby permitting the machine to operate on various sizes of enclosures and on papers of varying thicknesses and that the deflector plate is positively locked in position. It is also to be noted that by provision of the screws 109 the deflector plate 7 may be quickly and readily removed and replaced as occasion demands. I have further shown a means for adjusting the roller 12 horizontally depending upon the 90 size of envelope or enclosure being treated and that I have further provided a yielding contact between the oscillating plate 8 and the deflector plate 7 so that any adjustment of the deflector plate 7 is automatically taken up by the yielding contact and constant adjustment of the position between the lug 92 and plate 8 is avoided.

I have further shown mechanism for vertically adjusting the bottom register for the envelopes to accommodate various heights of envelopes, this adjustment being made from the outside of the machine and eliminating the necessity of removing any parts to accomplish the same and that the adjustment when once made can be permanently locked in the desired position.

It is further noted that I have described a means for registering the envelopes longitudinally and in view of the fact that the block 58 is secured to the shaft 59 by means of the set screw 116, it is a simple matter to adjust the block 58 along the shaft 59 to accommodate envelopes of varying lengths.

Automatic and manual stop mechanism

I have hereinbefore described generally the means for automatically stopping the machine when the envelope stacker is filled or 5 when no envelope is being fed from the magazines and I will now describe in detail the mechanism for accomplishing this result. In addition I will describe the means for stopping the machine manually from either 10 end thereof, that is, either the magazine end or the stacking end.

Referring to Figs. 21 to 24 inclusive, it will be seen that I mount on the inside of the frame Y an angular bracket 124 secured to 15 the frame by means of the bolts 124' and this bracket constitutes spaced arms 124² providing at their upper portions the spaced bearings 125 and at the lower portion the spaced 20 bearings 126. The bearings 125 in the upper portion serve as a support for the shaft 127 and one end of the shaft 127 is further supported by means of the angular bracket 128 secured to the frame Y by means of the bolt 25 128. Rigidly secured to the shaft 127 is the lever 129 and freely supported on the shaft 127 between the spaced bearings 125 is the hub 130 having formed integrally therewith the forks 130' carrying rollers 131 on the ends 30 thereof which are adapted to engage in the clutch groove 132.

On the free end of the lever 129 is the bent lug 133 and immediately above the bent lug is the roller 134. Integrally secured to the 35 hub 130 is an arm 135 provided with a bent lug 135' which is adapted to lie beneath the bent lug 133 and through the lugs 135' and the lug 133 is the bolt 136 which permits relative movement between the lugs 133 and 135'.

Integrally secured to the arm 135 and projecting laterally therefrom is the spring pin 40 138 to which is secured the spring 139 at one end and its opposite end is secured to a spring pin 139' projecting from the bracket 124.

The spring 139 normally pulls downwardly 45 or the arm 135 and inasmuch as the hub 130 is part of a bell crank lever the action of the spring 139 normally tends to keep the clutch in its disengaged position.

At the lower end of the bracket 124 are the 50 spaced bearings 126 in which is mounted the shaft 43 and rigidly secured to the shaft 43 is the latch 140 having cut on one side thereof the notch step 141.

Projecting laterally from the latch 140 is the spring pin 140' to which is secured the 55 spring 142 and which normally causes the latch 140 to stand in a vertical position with its edge resting against the face of the roller 134.

By referring to Fig. 21 it will be seen that 60 the clutch is illustrated in its engaged position with the lug 135' resting on the ledge or notch step 141 of the latch 140 and since the

spring 142 holds the latch against the roller 134 and the spring 139 is pulling the arm 135 downwardly, it will be seen that the bent lug 135' will engage the step notch 141 and the mechanism will therefore remain in its locked 70 position with the clutch teeth engaged in the clutch teeth of the pulley and that any force that might tend to disengage the clutch teeth will force the bent lug 135' against the step notch 141 thereby preventing disengagement 75 of the clutch. It is apparent, therefore, that in order to release the clutch from engagement with the drive pulley it is necessary to move the latch 140 out of engagement with the bent lug 135' and I have provided means for 80 accomplishing this either through the failure of envelopes in the magazine or through failure of an envelope to pass between the endless belts 20 and 21.

First describing the manual means for stopping the machine it will be seen that on the ends of the shaft 127 I provide the handles 143 and 144 at opposite ends of the machine and that movement of these handles causes rotation of the shaft 127 which forces the lever 129 downwardly, this being permitted because of the loose connection between the bent lugs 133 and 135' and as this link describes a circular path around the shaft 127 the roller 134 will wipe against the edge 146 85 of the latch 140 causing it to assume the position 147 as indicated in dotted lines in Fig. 21 thereupon releasing the bent lug 135 from the stepped notch 141 and permitting the spring 139 to pull downwardly on the arm 135, thereby 90 rotating the hub 130 about the shaft 127 and consequently throwing the forked arms 130' so as to disengage the clutch.

The reverse movement of the handles 143 or 144 will restore the clutch to its normal 95 position into mesh for as the link 129 is moved upwardly due to rotation of the shaft 127 it will pull upwardly on the arm 135 through the bolt 136 until the bent lug 135' is above the stepped notch at which time the spring 142 rotates the latch 140 and permits the stepped 100 notch to pass beneath the end of the bent lug 135' thereby restoring the mechanism to its 105 normal condition.

As has heretofore been stated the shaft 43 110 carries at its end the pin 42 by means of which the shaft 43 is caused to rotate. By reference to Fig. 21 it will be noted that when the latch 140 is caused to assume the position as shown in dotted lines at 147, the pin 42 assumes an 115 angular position and it will be seen, therefore, that the latch 140 which is rigidly secured to the shaft 43 can be swung into or out of locked 120 position by tilting of the pin 42 as well as by operation of the handles 143 and 144.

The tilting of the pin 42 can be accomplished either by pushing downwardly on one end thereof or upwardly at the opposite 125 end thereof. This pin is in practice tilted in this manner to automatically stop the ma- 130

chine because of the fact that the stacker is completely filled or because no envelope is being fed through the endless belts 20 and 21.

As has been previously described, when the 5 stacker is completely filled the lug 50 engages the stud 51, rocks the shaft 52 and pushes vertically on the rod 54 against the pin 42, thereby tilting the same and releasing the clutch.

10 If no envelope is being fed through the endless belts 20 and 21 the detector pin 38 in traveling forward causes the cam face 41 of the lever 40 to engage the pin 42 at the end opposite to that engaged by the rod 54 15 and pushes downwardly thereon, thereby rotating the shaft 43 to again disengage the clutch. From the foregoing, it will be seen that I have provided automatic means for insuring the proper operation of the machine 20 and that if for any reason whatsoever, no envelopes are fed through the machine, this fact will be instantly determined by the detector 38 and the clutch disengaged, thereby eliminating possibility of injury to the machine or to the material and that by automatically stopping the machine when the stacker is filled, constant attention of the operator is not required and piling up of the filled envelopes so as to foul the machine is 25 completely prevented and that in addition the machine can be stopped either from the stacker or magazine ends of the machine.

At this point attention might be called to the fact that the mounting of the secondary 30 envelope stop 37 on the shaft 148 and the suspension of the lever 40 on the same shaft might tend to confuse. This is explained by stating that the stop 37 is fastened integrally with the shaft 148 but that the lever 40 35 is mounted freely thereon and rocks independently of any action of the shaft 148.

The means for operating the stop 37 on the shaft 148 is shown in Fig. 21 and comprises a lever 204 integral with the shaft 148 and having at its upper end a roller 205 contacting with the face of the cam 206 against which it is held by a spring 207. In this manner upon rotation of the cam 206 the secondary stop 37 is given a reciprocating movement and is projected into and out of the path of travel of the envelopes between the endless belts 20 and 21.

In like manner the oscillating lever 40 is caused to reciprocate by having at its upper end the roller 205' contacting with the cam 206' and held thereagainst by means of the spring 207' all of which is clearly illustrated in Figure 21.

By the automatic or manual clutch operation I accomplish an important result in that it is very often found in automatic machines of this type that it is necessary to stop the machine. Ordinarily, so far as I am aware it is necessary to stop the motor. In stopping the motor the machines very often overrun

due to the momentum of the motor, thereby causing injury and damage to the various parts.

In the present device the motor continues to run but the operating parts of the machine are disconnected from the source of power and stop instantaneously upon disengagement of the clutch, thereby eliminating the possibility of any damage either to the parts of the machine or the material being treated.

Magazine construction

Referring now to Figures 25 to 27 inclusive, I have illustrated in detail the construction of the magazines employed in my machine and while I will describe merely the envelope magazine it is to be understood that the magazines 2 and 3 for the reception of the enclosures are identical in construction and that they are merely reversed in position so that the magazines 2 and 3 face the envelope magazine 1.

In these figures it will be seen that the envelope lies with the front face, that is the face on which the address is usually written, downwardly, and resting against the roller 4 and the flap end of the envelope is held between two back guides 149 and 150 which extend in a vertical position and are inclined as illustrated in Fig. 26 to receive the inclined edges of the open flap of the envelope.

The bottom edge of the envelope lies against the front guides 151, but the lower part of the stack lies against the guide plate 152 and the envelope is retained in this position by means of the side guides 153 and 154 which are adjustable on rods 169 and held securely by screws 170.

The guide plate 152 is journaled in the side frames X and Y by means of the reduced ends 155 and extends completely across the space between the side walls. Rigidly secured to the center of the guide plate 152 is an arm 158 as clearly illustrated in Fig. 25 and through which the stud 159 projects, the stud being riveted or otherwise secured to the cross brace and front guide support 160. The stud 159 is encircled by the spring 161 bearing at one end against the cross brace 160 and at its other end against the arm 158 which normally urges the arm 158 against the knurled knob 162 which is screw threaded on to the end of the stud 159 so that upon adjustment of the knurled knob 162 the plate 152 will be caused to swing about its pivot 155, thereby varying the space between the plate 152 and the roller 4 at the point 163 (Fig. 25).

I have described the back stops 149 and 150 as being inclined so as to receive the edges of the flap of the envelope when in open condition, but I desire it to be understood that the magazine is also capable of receiving envelopes with their flaps in closed condition and have indicated the position of such envelopes at 165 in Fig. 26.

In order to adjust the magazine to accommodate envelopes of various dimensions, I provide the back stops 149 and 150 mounted on rearwardly directed extension arms 166 carrying therein the slot 166' through which is projected the bolt 166² and have screw threadedly engaging the outer end thereof the nut 167 so that by loosening the nut 167 the back stops can be moved toward or away 10 from the front guides 151 and locked securely in the desired position.

The back stops 149 and 150 may also be adjusted vertically and to accomplish this result I provide the plates 153 and 154 with an 15 elongated slot through which is adapted to pass the bolt 166² and has threaded on its outer end the knob 167. The back stops 149 and 150 integrally carry the bolt 166² and it will be seen, therefore, that by loosening the knob 20 167 the vertical position of the back stops 149 and 150 can be varied.

In addition to the foregoing adjustments it will be readily seen from an inspection of Fig. 26 that the side plates 153 and 154 may be 25 adjusted to accommodate any width of envelope, the side plates being supported on the shafts 169 by means of the thumb screw 170. By loosening the screw and sliding the plates along the shaft 169 any width envelope 30 can be accommodated within the limits of the machine.

From the foregoing it is seen that the magazines are capable of adjustment so as to receive not only envelopes, but other matter 35 such as circulars, letters and the like of various sizes and dimensions and that the envelopes can be held in stacked relation either with the flaps open or closed and that an adjustment is provided to limit the gap or space 40 between the front guide and the feed roller 4 so as to permit feeding of envelopes one at a time and to accommodate envelopes of various thicknesses and yet permit of the deflection of the envelope or other mail matter into 45 a substantially vertical position so that the material will be caused to enter the feed rolls 5 and thence pass through the machine.

Intermittent drive mechanism

50 The feeding of the envelopes and the enclosures from the magazines is accomplished by means of an intermittent motion, that is to say, the feed rollers 4 are rotated during a certain period and rest during the remaining 55 period of operation so that sufficient time interval elapses between the feeding of envelopes to permit the insertion of the enclosures therein.

This intermittent driving as shown in Figs. 50 28, 29, 30, and 35 to 37 inclusive, will be described in connection with only one of the feed rollers, but it is to be understood that the same operation and the same construction is employed in connection with the other feed 65 rollers and since the parts are identical in

construction and operation it is thought to be necessary only to describe one of them.

Fig. 30 illustrates the roller employed in the present machine and it comprises a series of grooves 171 cut in its periphery and into which are passed commercial rubber bands 172 which adjust themselves in the grooves so as to expose one corner as at 173 for the purpose of contacting with the material to be fed and it is to be noted that by not gluing or otherwise securing the rubber bands in the grooves the bands can constantly change their position so as to expose new surfaces to the material being fed.

On the ends of the roller 4 are the trunnions 174 and 175, the latter of which is provided with a slot 176 and arranged in the side frames X and Y of the machine are the means for supporting and driving of this roller 4.

Referring now to Fig. 28, it will be seen 85 that the trunnion 174 is inserted in a tubular socket 177 and that the forked end 175 rides in the socket 178 through which passes the pin 179 adapted to engage between the forks of the end 176 for the purpose of driving the 90 roller.

The socket 178 is provided with a reduced shank 178^a projecting through the side wall of the machine and has at its outer end a nut or suitable securing device as indicated at 95 178'.

Rigidly secured to the reduced shank is the sleeve 180 on which is secured the ratchet wheel 181. Freely revoluble on the sleeve 180 is the cam sleeve 182 having one of its end faces provided with teeth as at 183 and at the other end the cam surface 184 is provided as shown in Fig. 35. This sleeve 182 is held against rotation by means of a ball 185 and a spring 186 located in the socket 186' in the side frame and normally urging the ball 185 outwardly which causes the latter to engage in one of the notches 183.

Referring to Fig. 29 it will be seen that the drive of the roller 4 is accomplished through the eccentric wheel 187 to which is attached the pitman rod 188 having at its upper end a yoke 189 provided with the ratchet teeth 189' which are designed to engage the gear 190, this gear being integral with the ratchet arm 191 (Figs. 36 and 37) and idling on the socket 178 at the point 192.

On the ratchet arm 191 is secured a pawl 193 which is normally urged into engagement with the ratchet teeth of the gear 181 by means of spring 194 (Fig. 29). It is apparent that movement which is imparted to the pitman rod 188 of the eccentric wheel 187 will cause the rack 189 to impart to gear 190 a circular motion which will in turn swing the ratchet arm 129 about the reduced portion of the socket 178, thus imparting to the ratchet wheel 181 a circular movement and since the ratchet 181 is fastened to the sleeve 180 and the latter rigidly secured to the socket 178 125 130

the roll 4 will be given a rotary movement until the pitman rod makes its return stroke at which time the pawl 193 will be disengaged from the ratchet 181 and slide over the teeth, thereby permitting the roll 4 to remain stationary during that period.

To prevent the roll 4 from continuing its rotation because of any momentum or to prevent backward movement of the roll 4 because of friction between the pawl 193 and the teeth 181 a spring pressure block 193^a is provided in the socket 177 and is arranged to resiliently engage the trunnion 174 of the roll 4, thereby frictionally holding the roll against retrograde movement or overrunning.

The friction between the pressure block 193 and the trunnion 174 can be varied by means of an adjustment screw 195 carrying on its end the block 196, the spring 197 being mounted between the blocks 196 and 193^a so that by turning on the nut 195 the spring can be compressed more or less as desired.

Attention is called to the fact that block 193^a has the pin 193^b passing therethrough and engaging in slots 198 in the tubular socket 177. This is to retain the spring in the socket.

Rigidly secured to the socket 177 is the knurled knob 199 and passing through the socket 177 and knurled knob 199 is the pin 200 which projects above the surface of the knurled knob 199.

Secured to the frame immediately above and overhanging the knurled knob is a plate 202 having an angular extension provided with a bayonet slot 201, the pin 200 being adapted to pass into the bayonet slot to lock the socket 177 from moving sideways and that when it is desired to move the roll 4 for any purpose a partial turn of the knob 199 to engage the pin 120 from the bayonet slot 201 will permit the socket 177 to be pulled laterally a sufficient distance to release the trunnion 174 from the socket 177 so that the trunnion 175 can then be removed from the socket 178 as will be readily understood.

It has been found in actual practice that in order for the machine to accommodate itself to various size mail matter it is necessary to adjust the intermittent feeding action of the roll 4 so that it can produce a longer or shorter feeding period as may be desirable.

I make provision for adjusting the feeding stroke of the roll 4 by means of the sleeve 182 or adjustment of the eccentric 187^a by means of set screw 187^b. The timing of the feeding stroke is controlled by adjusting the eccentric 187^a on the shaft 62 and the amount of feed is controlled by partially rotating and thereby adjusting the sleeve 182 to control the action of the pawl 193.

Attention is called to the fact that the pawl 193 is of sufficient width to engage the ratchet 181 and the cam surface 184 of the sleeve 182.

When the pawl rides on the surface 184 it is out of engagement with the ratchet teeth 181, the cam surface extending above the surface of the ratchet wheel 181, but at the moment the pawl drops from the face 184 to 184^a (Fig. 35), the pawl will engage in the ratchet and cause the roll 4 to be operated.

On the sleeve 182 I provide the operating handle 203 by means of which the sleeve 182 may be rotated so as to bring the cam surface 184 into any desired position so that the period of contact between the pawl 193 and the ratchet 181 can be varied to suit conditions. After the sleeve 182 has been adjusted to its desired position, it is maintained in its said position by means of the spring pressed ball 185 engaging the teeth 183 as has heretofore been described.

Adjustment of the eccentric 187 is also provided for by means of the set screw 187^b, it being obvious that by loosening this screw and setting the eccentric in any desired manner, and thereafter tightening the screw will produce the desired adjustment to properly time the rotation of the roll 4.

Roll adjusting mechanism

Referring now to Figs. 31 to 33 inclusive, I have illustrated a means for adjusting the tension between any two of the feed rolls, such adjustments being shown generally on Figs. 8 and 9, but for the sake of description, the construction will be described as being applied to one of the upper rolls of the pairs of feeding rolls.

Each roll of the pair comprises a reduced shank to which is secured a gear, the upper roll of the pair having the gear 213 thereon and the lower roll of the pair having the gear 214. The gears 213 and 214 are adapted to mesh so that proper feeding action between the rolls takes place and it will be seen from an inspection of Fig. 31 that the lower roll of the series is usually the stationary roll and the upper roll is so suspended under tension as to make it possible to adjust the same so as to permit material of any dimensions to be fed therebetween and as the thickness of the material changes the upper roll will be caused to move upwardly against the tension of the spring 218.

To provide for the adjustment of the upper roll I provide a bearing 210' having a reduced portion 219 which lies within the slot 207 in the plate 204 which is secured to the side frame of the machine by means of screw 205. The plate 204 is provided with an angular extension 206, at one end having an opening therein which is threaded to receive the bolt 212. The upper roll of the pair is journaled in the bearing 210. This bearing has an upwardly extending arm 210' provided with an overhanging angular ear 211 likewise provided with an aperture to receive the bolt 212, but which slides freely

therethrough. Disposed between the angular ear 211 and the head of the bolt 212 and encircling the bolt 212 is the spring 218.

Due to the screw threaded connection of 5 the bolt 212 with the angular ear 206 it will be seen that the tension between the pairs of rolls may be adjusted by turning the screw 212 against the tension of the spring 218 and it will be seen that due to this construction, 10 the upper roll of the pair is prevented from moving in any but a vertical direction against the tension of the spring 218. Therefore, it can be seen that any thickness of material can be fed between the rolls and that the rollers 15 accommodate themselves to these varying thicknesses.

In illustrating the present device I have shown merely the single envelope magazine and two enclosure magazines. However, I 20 desire it to be understood that I do not limit myself to any specific number of magazines and that more or less can be used as is found desirable.

In Fig. 9 I have indicated at 66 means for 25 securing additional eccentric wheels similar to the wheel 187 together with its associated pitman rod and mechanisms and at 63 in Fig. 8 I have illustrated the means of securing additional magazine units to the machine, 30 it being understood that if additional magazines are employed, they will be of exactly the same construction as those illustrated and described and that the driving mechanism for the feed roll of the added magazine 35 will be a duplicate of that already described in connection with the illustrated magazine.

The machine may be supported in any suitable manner, but in Fig. 8 I have indicated the machine as being supported on the 40 stand 64 provided with angular sockets 65 into which the feet of the machine are adapted to pass.

My machine is adapted to be driven by 45 means of an electric motor which I have indicated in Fig. 10 at M provided with a motor pulley M' over which the driving belt is passed to impart power from the electric motor to the pulley P (Fig. 21) and through the pulley to the gear train as clearly illustrated in Figs. 8 and 9.

It will be seen from the foregoing that I have provided a machine that intermittently feeds envelopes from a magazine in which they are placed in stacked relation into a vertical receiving position and that I feed one or more enclosures from stacked relation in enclosure magazines also into vertical position and that as the envelope reaches the vertical position it is arrested momentarily in 55 its path through the machine while the mouth thereof is opened and maintained in open position to receive enclosures from the enclosure magazine.

Immediately upon reception of the enclosures the envelope is permitted to resume its

movement through the machine and finally emerges therefrom into a stacking mechanism where the filled envelopes are arranged in orderly fashion and necessitate no further rearrangement.

Moreover, it is obvious that the machine is so designed as to accommodate practically all types of mail matter regardless of the thickness of stock employed, or the size or dimensions of the mail matter and that the machine requires little or no attention during operation due to the automatic detecting mechanism and stop mechanism by means of which the machine is brought to rest either upon failure of envelopes from the machine or because the stacker has been filled and in addition a manual means is provided for stopping the operating parts of the machine without stopping the motor, thereby eliminating possibility of damage to the machine due to momentum of the parts and the continuous strain incident to starting the mechanism.

What is claimed is:

1. The combination of a plurality of magazines adapted to contain envelopes and enclosures, means for feeding envelopes and enclosures downwardly from said magazines, means for checking the downward movement of the envelopes to support the same in a loading position, means for moving the envelopes horizontally and thereby registering the envelopes, means for distending the walls thereof, and means for feeding the enclosures into said envelopes while the envelopes are distended.

2. The combination of a plurality of magazines adapted to contain envelopes and enclosures, means for feeding envelopes and enclosures downwardly from said magazine, means for checking the downward movement of the envelopes to support the same in a loading position, a reciprocating register bar for moving the envelopes horizontally and thereby registering the envelopes, means for reciprocating said register bars, and means for feeding enclosures into said envelopes.

3. The combination of a plurality of magazines adapted to contain envelopes and enclosures, means for feeding envelopes and enclosures from said magazines, a laterally moving register bar for horizontally registering the envelopes, and means for feeding the enclosures into said envelopes.

4. The combination of a plurality of magazines adapted to contain envelopes and enclosures, means for feeding envelopes and enclosures from said magazines, reciprocating register bars for vertically registering said envelopes, a laterally moving register bar for horizontally registering the same, means for operating said register bars, and means for feeding the enclosures into said envelopes.

5. The combination of a plurality of magazines adapted to contain envelopes and en-

- 5 closures, means for feeding envelopes and enclosures from said magazines, register bars for registering the envelope both horizontally and vertically, means for operating said register bars, mouth distending means for said envelopes, and means for feeding the enclosures into said envelopes while the envelope mouth is distended.
6. The combination of a plurality of magazines adapted to contain envelopes and enclosures, means for feeding envelopes and enclosures from said magazines, register bars for registering said envelopes both horizontally and vertically, means for swinging certain of the register bars upwardly and downwardly for adjusting said register bars to accommodate various sized envelopes, means for distending the mouth of said envelope, and means for feeding the enclosures into said envelopes while the envelope mouths are in distended condition.
7. The combination of a plurality of magazines adapted to contain envelopes and enclosures respectively, means for feeding envelopes and enclosures downwardly therefrom, a relatively fixed deflecting plate interposed between the envelopes and the enclosures in the downward feeding thereof, means for feeding envelopes against one side of the deflecting plate to cause the same to assume a vertical position, means for clamping the flap of each envelope against the deflecting plate, means for feeding the enclosures against the opposite side of the plate to cause the same to assume a vertical position, and means for feeding the enclosures into said vertically positioned envelopes.
8. The combination of a plurality of magazines adapted to contain envelopes and enclosures respectively, means for feeding envelopes and enclosures downwardly therefrom, relatively fixed adjustable deflecting plate interposed between the envelopes and the enclosures during the downward feeding thereof, means for clamping the flap of each envelope against the deflecting plate, means for adjusting said plate to accommodate material of varying sizes and thicknesses, means for feeding envelopes against one side of the deflecting plate to cause the envelopes to assume a vertical position, means for feeding the enclosures against the opposite side of the plate to cause the same to assume a vertical position, and means for feeding the enclosures into said vertically positioned envelopes.
9. In a machine of the type described, the combination of an envelope magazine, enclosure magazines, means for feeding envelopes and enclosures downwardly from said magazines including a relatively fixed deflecting plate interposed between the envelopes and the enclosures during the downward feeding thereof, means for clamping the said envelopes by their flaps against the deflecting plate in enclosure receiving position with the body thereof distended to receive its enclosure, and means for feeding enclosures into said envelope.
10. In a machine of the class described, the combination of envelope and enclosure magazines, means for feeding an envelope downwardly from said envelope magazine and to a loading station including a relatively fixed deflecting plate interposed between the envelopes and the enclosures during the downward feeding thereof, means at the loading station for clamping the envelope flap against the deflecting plate so as to eliminate bulging of the wall of the envelope adjacent the flap folding crease, means for distending the mouth of the envelope, and means for feeding enclosures into said envelope.
11. In an envelope filling machine of the type described, in which envelopes and enclosures are fed downwardly, an envelope receiving and supporting plate, means for rocking the same from envelope receiving into envelope filling position, and a deflecting plate cooperating with said plate when the latter is in envelope filling position to clamp the envelope flap and support the envelope thereby, said deflecting plate extending above the envelope receiving and supporting plate and interposed between the envelopes and enclosures during the downward feeding thereof.
12. In a machine of the type described, the combination of envelope and enclosure magazines, means for feeding envelopes and enclosures downwardly therefrom including a relatively fixed deflecting plate interposed between the envelopes and the enclosures during the downward feeding of the same, means for arresting the progress of the envelope through the machine at a loading station, and means operable subsequent to the aforesaid envelope arresting means to clamp the envelope flap against the deflecting plate and support the envelope with its mouth in a distended condition.
13. In a machine of the type described, the combination of envelope and enclosure magazines, means for feeding envelopes downwardly from said magazines, including a relatively fixed deflecting plate interposed between the enclosures and envelopes during the downward feeding of the same, a reciprocating member in the path of movement of the envelope through the machine, means for reciprocating said member to release the envelope, and further means for clamping the flaps of the envelopes against the deflecting plate for suspending the envelope in filling position after the releasing movement of the reciprocating member.
14. In a machine of the type described, the combination of envelope and enclosure magazines, a movable stop, means for feeding an envelope downwardly from one of said maga-

zines and into engagement with said stop including a relatively fixed deflecting plate interposed between the envelopes and enclosures during the downward feeding thereof, means for moving said stop out of engagement with said envelope, means for clamping the envelope flap against the deflecting plate prior to the disengagement of the stop from the envelope whereby the envelope is suspended by its flap upon disengagement of the stop from the envelope, and means for feeding enclosures into said envelope.

15. The combination of a plurality of magazines adapted to contain envelopes and enclosures respectively, means for feeding envelopes downwardly and enclosures therefrom, a deflecting plate interposed between the envelopes and enclosures during the downward feeding thereof, a relatively fixed 20 clamping plate yieldingly engaging the deflecting plate and clamping the envelope flap therebetween, means for feeding the envelopes against one side of the deflecting plate to cause the same to assume a substantially vertical position on the clamping plate, means for feeding the enclosures against the opposite side of the deflecting plate to cause the same to assume a vertical position, and means for feeding the enclosures into said 30 vertically positioned envelopes.

16. In a device of the character described, the combination of an envelope magazine, enclosure magazines, means for feeding envelopes and enclosures from said magazines including a relatively fixed deflecting plate interposed between the envelopes and the enclosures during the downward feeding thereof, means for clamping the flap of the envelope against the deflecting plate to support the said envelope, opening finger engaging the envelope and movable outwardly to distend the mouth thereof, means for operating said finger, and means for feeding enclosures into said envelope.

45. 17. In a device of the character described, the combination of an envelope magazine, enclosure magazines, means for feeding envelopes and enclosures downwardly from said magazines including a relatively fixed deflecting plate interposed between the envelopes and enclosures during the downward feeding thereof, means for clamping the flap of the envelope to support the same thereby, reciprocating opening finger engaging the envelope, means for projecting the opening finger inwardly and then downwardly to engage the envelope wall and then rearwardly to separate said envelope walls, means for operating said finger, and means for feeding 55 enclosures into said envelope.

60. 18. In a device of the character described, the combination of an envelope magazine, enclosure magazines, means for feeding envelopes and enclosures downwardly from said magazines including a relatively fixed deflect-

70. 75. ing plate interposed between the envelopes and enclosures during the downward feeding thereof, means for clamping the flap of the envelope to support the same thereby, opening finger engaging the envelope and distending the mouth thereof, means for operating said finger, a yielding connection between said operating means and finger, and means for feeding enclosures into said envelopes.

19. In a device of the character described, the combination of an enclosure magazine, means for feeding envelopes and enclosures downwardly from said magazines including a relatively fixed deflecting plate interposed between the envelopes and enclosures during the downward feeding thereof, means for clamping the envelope in vertical position against the deflecting plate, opening finger engaging the wall of said envelope and distending the mouth thereof, means for operating said finger, a yielding connection between said operating means and said finger, and means for feeding enclosures into said envelope.

80. 85. 90. 95. 100. 105. 110. 115. 20. In a device of the character described, the combination of an envelope magazine, enclosure magazines, means for feeding envelopes and enclosures downwardly from said magazine including a relatively fixed deflecting plate interposed between the envelopes and enclosures during the downward feeding thereof, means for clamping the flap of each envelope against the deflecting plate, and reciprocating opening finger adapted to engage the wall of the envelope and distend the mouth thereof, the opening finger being so mounted as to permit the same to be swung out of normal position to permit access to inaccessible parts of the machine, and means for feeding enclosures into said envelopes.

120. 125. 130. 135. 21. In a machine of the class described, the combination of, a plurality of magazines adapted to contain envelopes and enclosures, means for feeding envelopes and enclosures therefrom, means for inserting said enclosures into said envelopes, a stacker receiving said filled envelopes, motor mechanism for driving said machine, and means for disconnecting said motor when the stacker is filled.

22. In a machine of the class described, the combination of, a plurality of magazines adapted to contain envelopes and enclosures, means for feeding envelopes and enclosures therefrom, means for inserting said enclosures into said envelopes, a stacker receiving said filled envelopes, motor mechanism for driving said machine, a clutch operatively connecting the motor with the machine, and means for disengaging the clutch when the stacker is filled.

23. In a machine of the class described, the combination of, a plurality of magazines adapted to contain envelopes and enclosures,

- means for feeding envelopes and enclosures therefrom, means for inserting said enclosures into said envelopes, a stacker mechanism receiving said filled envelopes, motor mechanism for driving said machine, means for disconnecting said motor from the machine when an envelope fails to feed through the machine and means for disconnecting said motor from the machine when the stacker is filled. 5 70
24. In a machine of the class described, the combination of, a plurality of magazines adapted to contain envelopes and enclosures, means for feeding envelopes and enclosures therefrom, means for inserting said enclosures into said envelopes, a stacker receiving said filled envelopes, motor mechanism for driving said machine, a clutch operatively connecting the motor mechanism with said machine, means for disengaging said clutch when an envelope fails to feed through the machine and means for disconnecting said motor from the machine when the said stacker is filled. 10 75
25. In a machine of the class described, the combination of, a plurality of magazines adapted to contain envelopes and enclosures, means for feeding envelopes and enclosures therefrom, means for inserting said enclosures into said envelopes, a stacker receiving said filled envelopes, motor mechanism for driving the machine, a clutch operatively connecting the motor mechanism with said machine, automatic means for disengaging said clutch when an envelope fails to feed through the machine and means for disconnecting said motor from the machine when the said stacker is filled. 15 80
26. In a machine of the class described, the combination of, a plurality of magazines adapted to contain envelopes and enclosures, means for feeding envelopes and enclosures therefrom, means for inserting said enclosures into said envelopes, motor mechanism for driving said machine, a clutch operatively connecting said motor with said machine, means for automatically disconnecting said motor from the machine when an envelope fails to feed through the machine, means for disconnecting said motor from the machine when the stacker is filled, and manual means for disengaging said clutch. 20 85
27. In a machine of the class described, the combination of, a plurality of magazines adapted to contain envelopes and enclosures, means for feeding envelopes and enclosures therefrom, means for inserting said enclosures into said envelopes, motor mechanism for driving said machine, clutch mechanism including an operating yoke connecting the motor with said machine, a stacker receiving said filled envelopes, automatic means for disengaging the clutch when an envelope fails to feed through the machine, means for disengaging the clutch when the stacker is filled, 25 90
- means for disengaging said clutch, and a lost motion connection between the clutch yoke and manual operating means to permit manual disengagement of the clutch without operating the automatic clutch disengaging means. 95
28. In a machine of the class described, the combination of, a plurality of magazines adapted to contain envelopes and enclosures, means for feeding envelopes and enclosures therefrom, means for inserting said enclosures into said envelopes, a stacker receiving said filled envelopes, motor mechanism for driving said machine, a clutch connecting said motor with said machine, means for disengaging the clutch when an envelope fails to feed through the machine means for disengaging the clutch when the stacker is filled, including a shaft, means operable from above the shaft upon failure of an envelope to feed through the machine for turning the shaft to disengage the clutch, and means operable from below the shaft when the stacker is filled to turn said shaft and disengage the clutch. 100 105
29. In combination, a plurality of magazines adapted to contain envelopes and enclosures, means for feeding envelopes and enclosures therefrom, means for inserting said enclosures into said envelopes, a stacker receiving said filled envelopes, motor mechanism, a clutch connecting the motor with said machine, means normally holding the clutch in disengaged position, a latch having a shoulder thereon, a yoke engaging said clutch and provided with an arm resting on said shoulder, and means operable upon failure of an envelope to feed through the machine to move said latch out of engagement with the shoulder to disengage the clutch. 110 115
30. In combination, a plurality of magazines adapted to contain envelopes and enclosures, means for feeding envelopes and enclosures downwardly therefrom, envelope reciprocating opening finger adapted to engage over the upper edge of the wall of the envelope and distend the mouth thereof, means for adjustably mounting said finger to accommodate envelopes of various sizes, and means for inserting the enclosures into said envelopes. 120 125
31. In combination, a plurality of magazines adapted to contain envelopes and enclosures, means for feeding envelopes and enclosures downwardly therefrom, and including a relatively fixed deflecting plate interposed between the envelopes and enclosures during the downward feeding thereof, means for clamping the flap of each envelope against the deflecting plate, and reciprocating opening fingers adapted to engage over the upper edge of the wall of the envelope and distend the mouth thereof, links connected to said envelope opening fingers, an operating lever connected to said fingers, means for fric- 130

tionally and removably engaging the operating lever and links with the opening fingers, whereby the fingers may be swung out of normal position to render interior parts of the machine accessible, and means for feeding the enclosures into said envelopes.

32. In combination, a plurality of magazines adapted to receive envelopes and enclosures, means for feeding envelopes and enclosures downwardly therefrom, a relatively fixed deflecting plate arranged to flex the envelopes and enclosures to vertical position and interposed between the envelopes and enclosures during the downward feeding thereof, a clamping plate cooperating with the deflecting plate and clamping the flap of the envelope therebetween, opening fingers for distending the side wall of the envelope, means for feeding an enclosure into said distended envelope, means for moving the clamping plate to release the filled envelope, and endless conveying elements below said clamping plate and adapted to receive the filled envelope therebetween when released from the clamping plate.

33. In combination, a plurality of magazines adapted to contain envelopes and enclosures, means for feeding envelopes and enclosures downwardly therefrom, a relatively fixed deflecting plate adapted to flex the envelopes and enclosures to vertical position and interposed between the envelopes and enclosures during the downward feeding thereof, a clamping plate cooperating with the deflecting plate to suspend the envelope by its flap, envelope opening fingers engaging the side wall of the envelope and distending the same, the said fingers being operable to tension the envelope thereby insuring insertion of the enclosure into the envelope, and means for feeding said enclosures into said envelopes.

34. In combination, a plurality of magazines adapted to contain envelopes and enclosures, means for feeding envelopes and enclosures therefrom, means for inserting said enclosures into said envelopes, a stop for arresting the passage of the filled envelopes through the machine, a movable detector pin for detecting the presence or absence of an envelope on said stop, motor mechanism, a clutch for connecting said motor with said machine, a clutch operating lever connected with the clutch and automatically movable to disconnect the machine from the motor, a latch engaging the clutch for holding the clutch in position for connecting the machine with the motor, and means actuated by the detector pin for moving the latch out of engagement with the clutch operating lever.

35. In combination, a plurality of magazines adapted to contain envelopes and enclosures, means for feeding envelopes and enclosures therefrom, means for inserting said enclosures into said envelopes, a stop for ar-

resting the passage of the filled envelopes through the machine, a movable detector pin for detecting the presence or absence of an envelope on said stop, motor mechanism, a clutch for connecting said motor with said machine, a clutch operating lever connected with the clutch and automatically movable to disconnect the machine from the motor, a cam movable with the detector pin, a pivoted latch engaging the clutch lever for holding the clutch in position for connecting the machine with the motor, and an arm connected with the latch and arranged in the path of the cam and adapted to be actuated by the same to move the latch out of engagement with the clutch lever.

In testimony whereof I have hereunto set my hand, this 9 day of January, 1929.

ELDRID L. BOUTON.
